UNITED STATES PATENT OFFICE.

MILTON M. DRYFOOS, OF NEW YORK, N. Y.

WEARING-APPAREL.

1,054,519.

Specification of Letters Patent. Patented Feb. 25, 1913.

Application filed September 14, 1912. Serial No. 720,437.

To all whom it may concern:

Be it known that I, MILTON M. DRYFOOS, a citizen of the United States, residing at New York, in the county of New York and State of New York, have invented certain new and useful Wearing-Apparel, of which the following is a specification.

This invention relates, generally, to wearing apparel; and, particularly, to petticoats or underskirts for women, and it has for its object to provide a garment adaptable, by a slight adjustment, to fit women having waist measurements varying from the normal smaller sizes to the normal larger sizes, whereby a dealer in such garments is relieved of the necessity of carrying in stock a wide range of sizes, and the invention consists in combining in the waist band of the garment a strip or strips of elastic, and plaits in peculiar arrangement as will be hereinafter more fully described and claimed.

In the accompanying drawings forming a part of this specification, Figure 1 is a rear elevation of a petticoat constructed according to my invention. Fig. 2 is a similar view showing two of the plaits "let out" to increase the measurement of the waist band. Fig. 3 is an elevation from the front with a portion of the waist band removed.

Similar letters refer to similar parts throughout all the views.

As is well known in the trade dealers in ready made wearing apparel are now compelled to keep in stock a wide range of sizes of each garment in order to be in a position to meet the requirements of their customers, with the result that the stock is burdened with garments of unusual sizes, smaller or larger than the normal, and for which the demand is infrequent.

Now, it is the purpose of this invention to obviate the necessity for a dealer to carry in stock a wide range of waist sizes in garments, and particularly the larger sizes, and at the same time to provide a garment the waist measurement of which may be readily and quickly adjusted to meet the requirements of a customer having a waist measurement greater than the measurement of the garment as it comes from the factory, and to accomplish this without the employment of skilled labor to make alterations or

changes therein to adapt it to fit the customer.

In carrying out my invention I secure short lengths of elastics A in or to the waist band B of the garment C by stitching the same thereto while the elastics are in their extended or stretched position, the stitching being made along the top and bottom of the elastics so that the material of the waist band or garment contracts into small folds a when the elastics are released. At one or the other end of the elastic at each side of the garment and, preferably, at that end adjacent the placket of the garment, the waist band is formed with a series of plaits D, made by folding the material of the waist band on itself and stitching the same at top and bottom, so that the folds lie flat, one on the other, and add but little to the thickness of the waist band. The folds or plaits may be of any desired or preferred width, and the number in each series may be regulated according to the number of sizes the waist band is designed to be adapted to fit but the number of plaits in each series should be the same, so that the placket shall maintain the same relative position at all times. In the present instance I have shown the waist band formed with six (6) plaits, arranged three (3) at each side of the garment, and the plaits are each one-half inch in width. Thus, supposing the waist band to be twenty three inches, and it is desired to adapt it to a waist measuring twenty-nine inches, all that is necessary is to let out, by cutting the threads, one plait at each side thus increasing the measurement two inches and adapting the garment to a waist measuring twenty-nine inches, the additional four inches required being given by the stretch of the elastics. With three plaits on each side and each plait one-half inch in width it will be seen that the letting out of all the plaits will increase the length of the waist band six inches to which is added the stretch of the elastic, two inches for each elastic, making a total increase of ten inches and adapting the garment to a size thirty-three waist.

Having described my invention what I claim is:

1. A waist band for wearing apparel hav-

ing plaited sections formed therein, and elastics arranged in the length of said waistband, whereby the measurement of the band may be increased by letting out the plaits.

5 2. A waist band for wearing apparel having elastics secured therein, and a series of plaits of uniform width formed in said band at each side thereof, whereby the measure-

ment of the band may be increased by releasing the plaits.

10 In testimony whereof, I affix my signature, in the presence of two witnesses.

MILTON M. DRYFOOS.

Witnesses:

J. RECHSCHIED,
MORTON WALLACH.
